MOUTH PROP

John L. Bloomheart, Toledo, Ohio, assignor to
Martha F. McKesson, Toledo, Ohio

Application May 17, 1939, Serial No. 274,147

2 Claims. (Cl. 128—12)

This invention relates to spacers for holding jaws apart.

This invention has utility when incorporated in devices for engaging the teeth or the gums in holding clearance therebetween as for opening access especially in dental work and even against rigidity which may be experienced as tending to develop in response to anesthetic as in analgesia and anaesthesia.

10 Referring to the drawing:

Fig. 1 is a side elevation from the tongue side of the device, the teeth of the patient being shown in dotted lines;

15 Fig. 2 is a side elevation of the device from the cheek or outer side;

Fig. 3 is an end elevation of the device from the insert or mouth open side;

20 Fig. 4 is a view looking into the device from the side as exposed to the teeth or gums;

25 Fig. 5 is a section on the line V—V, Fig. 2, showing the channel section with the position of the teeth and cheek dotted;

Fig. 6 is the blank from which this sheet metal core is formed for this denture device; and

30 Fig. 7 is a view of the formed blank for the rhomboidal core, looking into the channel side thereof.

Thin sheet metal blank 1 is shaped to provide tapering side 2 as the base of U-shaped channel from which risers 3 upwardly extend to have their free edges 4 outwardly bent. There is thus formed an open ended V-shaped channel providing a resistance core for composition or plastic body. This body provides bite portion 5 on opposite sides which may have transverse ribs 6 from lower flange or margin portion 7. Therefrom there is short portion 8 to tongue clearance portion 9 between these bite portions. Remote from this inner side of the mouth piece for this

35 denture device, there is major flange portion 10 having medial filler 11 therebetween. In completing this unit structure, opening 12 in the blank or metal reinforcing core provides a way in the composition coated body for forming port

40 13, through which string 14 may be inserted as a holder means permitting ready withdrawal of this device from position in use, wherein it may serve effectively to space teeth 15 or the gums 16 from which the teeth arise, thereby holding

45 mouth 17 open.

There is from cheek 18 as receding from lips 19 clearance 20 about the gums 16 outer portion into which may enter the flanges 10 from this dental device. Accordingly, in position for use, 50 the flanges 10 in the cheek side tend to hold the prop in position to spread the jaws and leave clearance 9 therebetween for the tongue of the patient. Therefore, the mouth is held open for such dental work as may be in order or other attention, say for throat or nasal purposes.

The device is accordingly one simply placed and at a desired insert position for determining the spaced relation, which, because of its taper, may vary the opening to which the device is effective. The experience with patients is frequently one involving difficulty in holding the mouth open for the desired attention, especially in the instance where anesthetic is used, as there is tendency many times for the mouth to become rigid or bite. This device is of sufficient physical strength to withstand such. Its coating, which may be a composition of rubber or analogous properties, is one not to tend to chip or shatter, even at excess of pressure. It is further effective against application of pressure tending to throw the device clear of the mouth. In the use, the physician, surgeon, anaesthetist, dentist, or one according attention to the patient, may gently spread the jaws of the patient and place this device, which is one readily cleaned and kept 5 antiseptic. As so placed for occasion of use, it will be retained thereby against shifting and leaves tongue clearance as well as not excess lateral spacing between the cheek and teeth so that there is factor of comfort to the patient.

10 In an emergency the string 14 may be pulled to effect withdrawal. The taper or V-form adapts for range of sizes or spread desired. However, there may be further range by adopting a size for infants and a second size for adults, 15 or even additional sizes as may be found desirable.

What is claimed and it is desired to secure by United States Letters Patent is:

1. A denture device providing a mouth prop 35 having a cheek-engaging convex portion of rhomboidal outline, the tapering sides of said outline forming outer flanges for a pair of spaced diverging trough portions inwardly overhanging from the cheek-engaging portion as a base of 40 approximately U-shape in cross-section, there being clearance between the trough portions to the inner side of the cheek portion as a tongue clearance region.

2. A denture device providing a mouth prop 45 having a reinforcing body, and resilient embedding means for the body having a cheek-engaging convex portion of rhomboidal outline, the tapering sides forming resilient outer flanges and therefrom a pair of spaced diverging trough portions inwardly overhanging from this cheek-engaging intermediate portion as a base of approximately U-shape in cross-section enclosing the reinforcing body and from which the reinforcing body extends across the bottom of the trough 55 and into inward flange portions of the trough, there being clearance between the trough portions to the inner side of the cheek portion to provide tongue clearance.
